UNITED STATES PATENT OFFICE.

JAMES M. DODGE, OF PHILADELPHIA, PENNSYLVANIA, ASSIGNOR TO LINK-BELT COMPANY, OF CHICAGO, ILLINOIS, A CORPORATION OF ILLINOIS.

PROCESS OF MAKING CHAIN-LINKS.

1,139,019.

Specification of Letters Patent. Patented May 11, 1915.

Application filed March 11, 1914. Serial No. 823,913.

To all whom it may concern:

Be it known that I, JAMES M. Dodge, a citizen of the United States, residing in Philadelphia, Pennsylvania, have invented 5 certain Improvements in a Process of Making Chain-Links, of which the following is a specification.

My invention relates to certain improvements in links of drive chains of the type 10 having an open center for the reception of the tooth of a sprocket wheel and having a cross bar at one end and a hook at the opposite end for the reception of the bar of an adjoining link. The links are made detachable, one from the other, and are also made interchangeable.

This application is a companion application to one filed by me on the 8th day of February, 1913, Serial No. 747,101, and also to one filed by Karl Dodge on the 8th day of February, 1913, Serial No. 747,135.

The object of my present invention is to improve the construction of a link of the type above described and to make the quadrangular body portion from a round bar, flattened and shaped so as to be readily united to the hook member by welding, in order to make a substantial link which will be a substitute for the present malleable iron 30 link and which will be interchangeable therewith. This object I attain in the following manner, reference being had to the accompanying drawings, in which:

Figure 1, is a perspective view of my improved chain link; Fig. 2, is a longitudinal sectional view on the line *a--a*, Fig. 3; Fig. 3, is a plan view; Fig. 4, is a transverse sectional view on the line *b--b*, Fig. 3; Fig. 5, is a transverse sectional view on the line *c--c*, Fig. 3; Fig. 6, is a longitudinal sectional view on the line *d--d*, Fig. 7, showing the body portion and the hook member assembled prior to welding; Fig. 7, is a plan view of the link prior to assembling; Figs. 8 and 9, are plan and side views, respectively, illustrating the first step in the process of forming the body portion by flattening a round bar; Figs. 10 and 11, are views of the second step of the process, showing 50 the cutting of the flattened portion; Figs. 12 and 13, illustrate the third step in the

process, in which the edges of the tapered and flattened portions are rounded and finished; Fig. 14, is a view of one of the blanks cut from the bar; Fig. 15, is a view showing the blank bent at each end; Fig. 16, is a view showing the blank bent to form the quadrangular body portion; Fig. 17, is a view of the finished body portion ready to have the hook members applied thereto, as in Fig. 7; Fig. 18, is an enlarged perspective view of one of the hook elements showing the first step in the process of making the same; Fig. 19, is an enlarged view of one of the hook elements showing the second step in the process of making the same; and Fig. 20, is a perspective view, showing the hook elements assembled to fit the body portion, as illustrated in Fig. 7.

Referring to the drawings, 1 is the body portion of the link made rectangular and having an open center into which the teeth of the sprocket wheel can project. This body portion is made from a round bar in the present instance, and is bent into shape to form the round end bar 3, tapered side bars 4, and the flat end members 5, Figs. 6, 7 and 17. The two end members 5, in the present instance, are preferably arranged to contact one with the other within the hook section 2, as illustrated in Fig. 7.

The hook section is made of a series of blanks 6, assembled side by side, and these blanks have a socket 7 for the reception of an end bar 3 of an adjoining link and are slotted at 8 directly back of the socket to receive the end members 5 of the body portion. When the two parts are assembled, they are secured together, preferably by welding, so as to make an integral link. The slot 8 in the hook member 2 is arranged at an angle, as clearly illustrated in Fig. 6, and the end member 5 of the body portion is also arranged at the same angle and these end members are of a greater depth than the balance of the body portion and preferably extend above the upper surface of the hook member, as in Fig. 6, to allow sufficient metal to make the proper weld. These members 5 are flat and the slot 8 is comparatively narrow so as to decrease the distance between the front and rear of the hook member and

yet to allow sufficient metal to make a firm union between the two parts.

It is essential, at the present time, that the link should interchange with an ordinary 5 standard malleable link of the same size or number, and by making the link as above described it will interchange.

I make the blank for the body portion in the following manner:—A rod of a diameter 10 to fit the socket member is flattened at intervals, as shown at 9, Figs. 8 and 9, so as to increase its width and to reduce its depth. Then this flattened portion is shaped by cutting away the depression on each side of a central projection 10, as illustrated in Figs. 10 and 11. This, however, leaves sharp corners at the edges 11 and 12. The blank is then placed 15 in dies, which round the edges 11 and 12, as illustrated in Figs. 12 and 13. The blank 20 is then in condition to be cut in the proper length, as illustrated in Fig. 14, and I preferably make the blanks so that one end member 5 will be of a greater length than the other member 5, so as to break joints with 25 the sections of the hook member, as illustrated in Fig. 7. In this instance, there are four sections of the hook member, but, where the number is uneven, the ends 5 can be of 30 the same length. The ends are then bent, as 35 illustrated in Fig. 5, at the point x , x , Fig. 14 to form the end members, and are finally bent at y , y , Fig. 15, so as to form the tapered side members, as illustrated in Fig. 16. The blank is finally shaped in suitable 40 dies so as to bring the ends of the end member 5 substantially in contact, as in Fig. 17, and to reduce any fins which might be formed on the body portion. At this step in the process the notches 13 are formed so that 45 the links can be coupled by sliding the end bar into the socket of an adjoining link.

The blanks for the hook member 2 are punched from sheet metal and notched at the upper edge back of the socket 7, as at 14, 45 Fig. 18. Then the blanks are assembled and cut by a suitable tool to form a deep slot 8, Fig. 19. The mouth of the slot is preferably enlarged by beveling the side walls, as shown at 15, Figs. 6 and 19, and as the end 50 bar extends above the hook member it provides sufficient metal to properly make the slot. The weld is usually made by an acetylene flame and the excess metal of the hook member and the body portion is sufficient 55 to make a proper weld, but it will be understood that additional metal may be added in some instances, without departing from the essential feature of the invention.

The finished weld will have the appearance, as illustrated at w , Figs. 1 and 2, and an additional weld may be made as at v , Figs. 1 and 2, to unite the sections of the hook member together at the point of the hook.

A link made in accordance with my invention has been tested and compared with a malleable link of the same standard size, and it is stronger than the malleable iron link and can be manufactured at a less cost.

I claim:—

1. The process herein described of making a quadrangular body portion of an open rectangular link, said process consisting in first flattening a round bar at intervals; cutting a portion of the flattened part away to leave 75 a portion of a greater width than the round portion; then severing the blank at the flattened part; then bending the flattened part near the ends of the blank to form the end members; and bending the blank at the 80 round portion to form the end bar and side bars.

2. The process herein described of making a quadrangular body portion of a chain link, said process consisting in flattening and 85 tapering a portion of a round bar so as to increase its width; then cutting the surplus metal from the flattened and tapered part, leaving an extension on one side to form the end members of a link; then cutting the 90 blank at the flattened part; and finally bending the blank into quadrangular shape.

3. The process herein described of making a quadrangular body portion of a link, the same consisting in first flattening a round 95 bar at intervals; removing a portion of each flattened part, leaving a projection at one side thereof; then cutting the bar into lengths at the flattened parts, so as to form blanks with projections at each end; and 100 then bending the blank into quadrangular shape with the flattened portions abutting.

4. The process herein described of making the quadrangular portion of a link, said process consisting in flattening and tapering 105 a bar at intervals so as to increase the width of the bar; removing the surplus metal from one side of the flattened part of the bar and removing portions of the metal from the other side of the bar, leaving projections at 110 intervals; cutting the bar at the projections so as to form blanks having enlargements at one side and at each end; then bending the blank to form the quadrangular body portion having a round bar at one end and the 115 flat members at the other end, with tapered side members.

5. The process herein described of making a quadrangular chain link, said process consisting in flattening a round bar at intervals 120 to increase its width; removing the surplus metal at one side of the flattened portion of the bar so that that side of the blank will be straight; removing portions of the metal at the other side of the bar to leave projections 125 at the flattened portions; rounding the bar at each side of the projections and at the opposite side of the bar; cutting the bar at the

projections, forming a blank with the projections on the same side and at each end; bending the blank at each side of the round central portion and bending it at the end of the flattened portions so as to form a round cross bar and flat end members of a greater height than the cross bar.

In testimony whereof, I have signed my name to this specification, in the presence of two subscribing witnesses.

JAMES M. DODGE.
